UNITED STATES PATENT OFFICE.

FRANCIS HARLEY DAVIS, OF MELBOURNE, VICTORIA.

CORE-BOARING APPARATUS AND MEANS FOR GRIPPING AND RAISING CORES THEREWITH.

SPECIFICATION forming part of Reissued Letters Patent No. 11,597, dated April 27, 1897.

Original No. 555,640, dated March 3, 1896. Application for reissue filed July 17, 1896. Serial No. 589,578. Patented in Victoria August 19, 1893, No. 10,747, and in Western Australia September 12, 1894, No. 526.

To all whom it may concern:

Be it known that I, FRANCIS HARLEY DAVIS, a subject of the Queen of Great Britain and Ireland, and a resident of Melbourne, in the Colony of Victoria, have invented a certain new and useful Core-Boring Apparatus and Means for Gripping and Raising Cores Therewith, (patented in Victoria, No. 10,747, dated August 19, 1893, and in Western Australia, by Letters of Registration No. 526, dated September 12, 1894,) of which the following is a specification.

My invention is designed to effect improvements of an important kind in boring machinery, whereby I render practicable much greater economy of working expenses, economy in the cost of the plant employed, and when prospecting or testing country for deep leads or coal measures the securing of a truer and more reliable record of the strata as they are reached than is often arrived at by means of the diamond drill or other known apparatus. In such apparatus the cores obtained are often very incomplete, large portions having been ground away and washed to the surface, and there is no method of satisfactorily checking such losses and obtaining a correct record of the thickness of seams of coal or other strata pierced.

My improvements are extremely simple and relate, first, to a cutting-tool; secondly, to a chip-cup apparatus for debris, and, thirdly, to a means and apparatus (by introducing sharp fragments of hard rock or the like down the tubing and around the core and by means of a frustum of an inverted cone which forms the interior upper portion of the cutter) whereby I am able, as hereinafter set forth, without expense or uncertainty, to cause the core to be gripped, broken off, and raised with the rods from time to time, as required.

Referring now to the accompanying sheets of drawings, which form a part of this specification, and in which the same letters of reference indicate like parts, Figure 1 shows my apparatus in vertical elevation complete, as it would appear at work boring the earth's strata, the latter being shown in section. Fig. 2 shows in vertical middle section the same parts of the apparatus as in Fig. 1. Fig. 3 is a

sectional plan of the boring-rod and the chip-cup with its steadyng-pins. Fig. 4 is a sectional elevation of the reducing-plug, showing the boring-rod coupled to the same and showing the upper end of the core-barrel and the base of the chip-cup. Fig. 5 is a sectional elevation showing the base of the core-barrel and the frustum of an inverted cone formed in the upper portion of the cutter, which portion is shown screwed into position and reduced in diameter at the threaded portion, so as to leave a shoulder against which abuts the end of the threaded core-barrel D. Fig. 6 shows my rock-cutter, and Fig. 7 a coal-cutter, both in vertical elevation. Figs. 8 and 9 show, respectively, plan views from below of the said rock and coal cutter. Fig. 10 shows a horizontal section of the rock-cutter on the line X X in Fig. 6.

Referring to the drawings, in which Figs. 1 and 2 are upon a smaller scale than the others, A shows a hollow boring-rod and represents the lowermost of the usual series of coupled tubes which extend to the surface and are caused to rotate when boring is in progress.

B shows a novel chip-cup consisting of a plain cylinder or series of connecting cylinders and located above the core-barrel, so that when in use its base is closed and it forms an annular cup having a certain specific capacity, hereinafter stated.

C is a reducing plug or coupling, part of its length being shown screwed into the upper end of the core-barrel D, or it may be shrunk into and riveted or otherwise secured to the same. This plug has internally a female screw, as shown, into which the lower end of A is screwed home to its seat, as shown. The plug has also a shoulder of the same diameter as the core-barrel, which shoulder prevents the plug going too far down. The base of the chip-cup B is slipped down, (and fits closely over a part of C, which projects above D,) resting on the shoulder aforesaid. There is a bayonet-slot II in the projecting portion of C and an internally-projecting pin I near the base of the cup B, by which these parts are kept locked together when in the bore. The base of the bayonet-slot extends in the reverse direction to that in which the

tubes are rotated, so that there is no tendency for the cup to become displaced.

J J J show pins at the upper extremity of the chip-cup, serving to keep it with its sides parallel to the boring-rod, which passes through it. In F, the rock-cutting bit, there is a series of spiral grooves of wide pitch K K, there being for each cutting-tooth one groove, which is not merely a shallow depression to act as a channel for water and finely-divided debris, but is cut deeply, as shown in Fig. 10, so as to allow large chips to ascend and also allow of gulleting the teeth when worn. The edges of any groove coincide with different edges of the same tooth, whose respective edges are longitudinal and spiral.

My cutter is novel, and by having the teeth in this shape and far apart the action is different from that of ordinary drills.

Instead of pulverizing the rock into very fine parts, my cutter when slowly rotated under great pressure has the effect of removing large flakes which I call "chips." I will again refer to the cutter F in a later part of this specification. In some cases I use vertical grooves K', as shown by dotted lines in Fig. 6, instead of spiral ones.

This apparatus is worked in the usual manner by rotating the series of hollow rods A, and thereby the core-barrel D and the rock or coal cutting bit F or G, water being at the same time forced through the interior of A and D to the bottom of the bore, and where it rises up and around the exterior of the tubing, as in the working of diamond drills and other hydraulic boring-machines. The water, as it escapes under the gullets of the teeth of the cutter and begins to ascend, carries with it the chips and powdered particles of mineral matter as fast as they are produced by the boring-bit.

Now in all diamond and other hydraulic drilling machinery the whole or almost all of the cuttings or chips are caused to pass with the water up the bore to the surface, and to do this these drills require extremely powerful special steam-pumps when any considerable depth is attained. Thus it is that the cost of drilling at great depths with such drills and the cost of plant, as well as the quantity of water employed, are all excessive. The weight of the rock-cuttings held in the water becomes at length so great that a point may be reached where the influence of gravity cannot be overcome by the process of pumping except at a practically prohibitive expenditure of power. I proceed on totally different principles. I provide that the chips and debris shall never be carried up to the surface by the ascending water, and instead of a powerful steam-pump an ordinary hand-pump suffices for my apparatus, no matter how deep the bore may be, it being essential to avoid having such powerful currents as I have referred to.

The current from my comparatively weak pump does not lift the debris far up the bore,

so that water from bores made with my apparatus reaches the surface only slightly loaded with impurities.

I have found that the contrivance B renders my plan a success.

B is a cylinder (preferably a series of connectible cylinders) forming one long annular cup around the lowest boring-rod and immediately above and of uniform diameter with the core-barrel, and it has this essential characteristic which distinguishes it from all other inventions and without which it would fail to answer the purpose for which it is used, that it is approximately of such length as to be able to hold all the debris which the cutter removes while filling the core-barrel with core. The object of having disconnectible sections is that they enable the cup to be emptied without trouble when required. This rigid and lengthy cup is capable of containing the solid contents of bore displaced during one operation—that is, from inserting the tool till withdrawing the same. It also serves to keep the whole boring apparatus true to its vertical line, a matter in respect to which other boring apparatus is prone to give some trouble.

Having then provided such a cup which is definitely able to contain all the debris aforesaid and having a jet of water no more powerful than is necessary to carry the debris above the top of the chip-cup, at which point the speed of the current diminishes on account of the widening of the water-space in the bore, the result is that the chips fall into the cup and fill it in regular order as they are produced, thus making an inverted but accurate record of the strata passed through, and the larger the chips the more promptly they are disposed of by their falling into the cup, whereas in cases where the chips are forced to the surface the larger the chips the greater is the power needed to dispose of them.

When my apparatus is caused to cease boring and there is a length in the core-barrel ready to be drawn, I cease pumping almost immediately, as in two or three minutes the last of the chips will have been lodged in the cup. In the case of the diamond drill in deep bores the pumping must go on, often for an hour, till the greater part of the debris has been washed out, and even then there is often enough fine mineral matter left in the bore to be a source of trouble under various well-known circumstances. Such is not the case with the apparatus I use, which leaves the bore practically clean and free from debris. As soon as my tubes are drawn I empty the various sections of the chip-cup, keeping the strata in order, and also empty the core-barrel and check the core by the cuttings. If the core is perfect, there will be a definite proportion, such as one pound of core to two pounds of cuttings, and the various kinds of minerals in both core and cup will closely correspond. Any discrepancy in the core can be detected

and the extent calculated by noting to what extent the contents of the core and the cup depart from the proper definite proportions. By noting to what extent the respective contents of cup and barrel depart from these conditions as to kind and quantity it will be known to what extent the cores fail to give a true and complete record of the strata, as happens when one length of core rides or 10 grinds upon another length beneath it.

It will be seen that the rock-cutter F is of peculiar and novel construction, and as it produces large chips would be impracticable in deep-boring apparatus unprovided with 15 my chip-cup. It is composed of a cylindrical piece of steel with large teeth cut in the end, as shown in Fig. 6, these teeth being of sufficient length (about two and one-fourth inches) to make it an easy matter to draw 20 them out and dress them upon an anvil like an ordinary pick-point. When these teeth wear short, a portion of the gullet (which is that portion of the lower edge of the cylinder that is located between the upper rear 25 face of one tooth and the front face of the next adjacent tooth) can be cut away, which will renew the length again and again as long as the cylinder shall last. The spiral grooves K or the vertical grooves K' are for a twofold 30 purpose—viz., to make more clearance for the chips to flow upward and to make the metal lighter to cut out when gulleting. These teeth, which may be any even number, preferably six, but not less, are set in and out 35 alternately like saw-teeth. The inside set cuts the rock so as to leave free passage for the water between the core-barrel and the core, while the outside set cuts clearance for the whole apparatus to work freely and to 40 allow water and chips to ascend to and enter the top of the cup. Thus the spaces between the respective surfaces of the bore and the core and the cutter form the waterways referred to.

45 In Fig. 7 a bit G to cut seams of coal is shown, it being interchangeable with the rock-cutter F. The machine would not be complete without it, as when coal is reached the coarse teeth of F would fracture the core and 50 destroy it.

G is made of a steel cylinder, the bottom end being cut into six sections set in and out alternately, as already described and as shown in Fig. 7, each section consisting, not 55 of one tooth, as in F, but of a number of fine saw-teeth. The slots between the sections allow free egress for the water, being a modification of the gullets in F, and vertical grooves K' in G take the place of the spiral 60 grooves in F.

I have now to describe the simple method by which I break off and raise cores to the surface and which is applicable to diamond and other drilling apparatus. When the boring has ceased, I preferably take some quartz-rock and crush it to about the size of peas. This produces fragments of great hardness

with sharp edges, and these I drop from above down the inside of the coupled tubes A, whereby they fall into the core-barrel D and around 70 the core. According to the sizes and shapes of the fragments they find a bed at different parts within the core-tube, but principally between the core and inversely-coned sides N of the interior of the upper portion of the 75 cutter F or G, at which part the wedging action is most powerful. A revolution or two of the tubing is then sufficient to embed and wedge the edges of the fragments so firmly into the core and between the latter and the 80 barrel and the part N that no other gripping appliance whatever is necessary. By the revolution last named the core is often broken off at the base, but if not it is broken off or torn up by lifting, and the whole of the rods 85 being then raised the core will come up to the surface firmly gripped within its barrel.

In carrying out my said method of gripping and raising cores any suitable substitute for quartz-rock may of course be employed, provided the particles are irregular forms.

By doing without the gripping arrangements hitherto used and by gripping cores in the manner described by me I am enabled to 95 avoid the necessity of cutting away a wide annulus around the core, as is done where it is necessary to give clearance for the space required for gripping appliances to work in. The importance of this will be clear, since 100 the less debris there is cut away around the core the faster and cheaper the boring will be done.

The cores from my boring apparatus show great freedom from spiral groovings, the advantage of which is obvious. I procure this result by using heavy pressure and comparatively slow rotation, whereby the lashing that produces the groovings is avoided.

What I claim is—

1. A tubular cutter consisting of a cylindrical metallic shell having a series of teeth formed integral with one of its ends, said teeth being formed with practically straight front and rear faces, the front face being vertical, 115 while the rear face is formed at an angle of thirty-five degrees or less, from the vertical, substantially as set forth.

2. A tubular cutter consisting of a cylindrical shell having a series of teeth formed integral with one of its ends, said teeth, each being formed with a vertical front face and a straight inclined rear face and being separated from each other by gullets, substantially as set forth.

3. A tubular cutter consisting of a cylindrical shell having a series of teeth formed integral with one of its ends, said teeth each being formed with practically straight front and rear faces, the front face being vertical 130 while the rear face is formed at an angle of thirty-five degrees or less from the vertical, and a series of grooves formed on the outer surface of the cylinder, each groove termi-

nating between two adjacent teeth, substantially as set forth.

4. The combination with a tubular cutter, core-barrel and hollow boring-rod, of an inclined annular wall located above the teeth of the tubular cutter, and arranged and adapted to permit hard fragments of suitable material to be fed from above through the hollow boring-rod and enter the wedge-shaped space formed between the core and the inclined annular wall, substantially as set forth. 30
5. The combination with a hollow boring-rod, and a chip-cup surrounding the boring-rod, of a cutting-bit adapted to be rotated by the boring-rod and adapted to cut a bore of greater diameter than the chip-cup, said hollow boring-rod serving to convey a supply of water from above the chip-cup to the core-barrel located below the chip-cup, substantially as set forth. 40
15
20

6. The combination with a core-barrel, tubular cutter provided with metallic teeth, attached to the lower end of the core-barrel, and a chip-cup to its upper end, of a hollow boring-rod extending through the chip-cup and serving to supply water from above to the tubular cutter, substantially as set forth. 45
25

7. The combination with a core-barrel, chip-cup and tubular cutter, detachably screwed

together and forming a continuous cylinder of practically uniform exterior diameter throughout its length, of a hollow boring-rod extending through the chip-cup and serving to supply water from above to the tubular cutter, substantially as set forth. 35

8. A grab for lifting cores or the like consisting of the combination of a tubular cutter whose interior diameter is greater and exterior diameter less above the teeth than at the teeth, a core-barrel D, whose interior diameter exceeds that of the cutter and communicating with the said cutter by the inversely-conical channel whose surface is N, a tube A open throughout its length and connected to and communicating with the said core-barrel, and an annular chip-cup closed at its lower end surrounding the said tube A open at its upper end and of less exterior diameter than the exterior diameter of the cutter at the teeth. 40
45

In witness whereof I have hereunto set my hand in the presence of two subscribing witnesses. 50

FRANCIS HARLEY DAVIS.
